PATRICK M. FURLONG, OF NEW YORK, N. Y.

METHOD OF BENDING ELECTROTYPE-PLATES.

956,522.

Specification of Letters Patent.

Patented May 3, 1910.

Application filed January 14, 1909, Serial No. 472,210. Renewed February 4, 1910. Serial No. 542,072.

To all whom it may concern:

Be it known that I, PATRICK M. FURLONG, of the city of New York, county of Kings, and State of New York, have invented a new and Improved Method of Bending Electrotype-Plates; and I do hereby declare that the following is a full, clear, and exact description thereof, which will enable others skilled in the art to use the same, reference being had to the accompanying drawings, forming part of this application.

An obstacle to the successful and economical use of two-color printing-presses in printing from both flat and curved electro-type or other printing plates on the same job, has been the necessity for bending the electrotype plates twice, melting away the backing between each bend, and re-backing with metal. This is made necessary by the fact that when an electrotype or other printing plate is curved for printing on a press cylinder, the process of curving stretches the plate, so that it is longer on the printing face when curved than when flat; and in consequence the impression from such curved plate does not register with the impression from flat plates of the same work. The same difficulty obtains when separate parts of a work are printed on cylinders of different diameters.

In this present application I describe an improved method of bending or curving electrotypes and other printing plates, which prevents the stretching of the plates while being bent or curved, thus producing bent or curved plates having the length of the printing face the same as that of flat plates of the same job or work, and giving an impression in register with the impression from the flat plates.

Figure 1 is a perspective view of the plate-holder. Fig. 2 is a perspective view of a removable wedge-shaped member. Fig. 3 is a perspective view of the plate-holder with the flat electrotype plate secured thereon. Fig. 4 is an end elevation of a form of press for giving the curvature to the plate. Fig. 5 is a perspective view of the completed plate after being operated upon by the dies of the press.

In the accompanying drawings: Fig. 1 represents a perspective view of a plate-holder, *a*, consisting of a flat plate of resilient material, preferably steel, having guides or cleats *b*, and *c*, disposed upon its surface at a distance apart to conveniently

receive an electrotype plate between them with some space at one end. Guide or cleat *c* is wider at one end than the other, and is wedge-shaped.

Fig. 2 is a perspective view of a wedge-shaped member or elongated piece of material, flat, and having one end wider than the other.

Fig. 3 is a perspective view of the plate-holder *a* with a flat electrotype plate *f*, laid flat upon the surface of the plate-holder *a* between the cleats or guides *b* and *c*, and with a piece of card-board or paper *e* between the flat surfaces of the plate and plate-holder. The wedge-shaped member *d* is shown in position between one end of electrotype plate *f*, and the fixed guide or cleat *c*.

Fig. 4 is an end view of an ordinary press having a convex die *g* arranged to fit firmly into a concave die *h*. The plate-holder *a* with the electrotype plate *f* lying flat upon the card board *e* is shown between the dies *g* and *h*, in position for pressing.

Fig. 5 is a perspective view of the plate *f* in its curved condition after receiving the impress of the dies in the press. The plate-holder *a* and card board *e* are shown returned to their original flat condition through their resiliency.

In performing the method, the flat electrotype plate, as shown at *f*, in Fig. 3, is placed with the printing-surface down on the flat surface of the improved plate-holder *a*, with a card-board, *e*, between the surfaces, to prevent abrasion of the type-faces. The electrotype plate is placed on the plate-holder between the cleats or guides *b* and *c*, and the separate wedge-shaped member *d* inserted between the cleat or guide *c* and the end of the electrotype plate, and driven home, so that its sides tightly engage with the cleat or guide *c* and with the electrotype plate *f*, thus forcing the plate *f* firmly against the cleat *b* on one side, and the wedge *d* on the other.

The plateholder with the card-board and the electrotype plate held tightly between the guides by the impact of the wedge, is placed between the convex and concave dies of a press, as shown in Fig. 4, and the dies brought together by turning down the press in the usual manner. The dies of the press are then separated, by reversing the press, the plateholder removed with its contents of plate and card-board, and the wedge removed from between the end of the electro-

type plate and the guide or cleat. The plate-holder and card-board return to their original flat condition, wholly or nearly so, by reason of their resiliency. The result of this 5 operation is to produce an electrotype plate bent to the segment of a cylinder as shown in *f*, Fig. 5, and which has its printing surface of the same length as it was when the electrotype plate was flat, before being 10 pressed. This result is due to the softer metal of the electrotype plate being held by the guides or cleats upon the plateholder, which is stronger than the electrotype plate, and prevents it from stretching in the process 15 of pressing.

In speaking of the printing surfaces of a flat plate and a curved plate produced by my process being the same in length, I desire to include this sameness of length in curved 20 plates of differing degrees of curvature, when my improved method is used.

The use of a plate-holder of resilient material on the side of an electrotype plate, with a buffer of cardboard or paper between 25 the plate and the plate-holder, during the process of bending, is now in common use in the art as here shown; as is also the use of a press with convex and concave dies, or a concave die and rollers, to bend or curve the 30 plate, and I do not claim any of these steps as new.

What I claim as new is:

1. The herein described method of bending or curving electrotype plates, which consists in confining the edges of the plate parallel to the axis of the bend or curve and 35

then bending or curving said plate while held against stretching.

2. The herein described method of bending or curving an electrotype plate which 40 consists in placing the flat electrotype plate upon a support with the printing surface downward, interposing an anti-abrasion member, tightly confining the sides of the electrotype plate parallel to the axis of the 45 bend and then bending the plate.

3. The herein described method of bending or curving electrotype plates which consists in tightly wedging the opposite sides thereof against a support and confining said 50 sides parallel to the axis of the curve, then subjecting the same to the action of curved dies, then removing the holding means and allowing the support by its resiliency to assume its original flat condition. 55

4. The herein described method of bending an electrotype plate which consists in placing upon a support a resilient bed, placing on said bed an electrotype plate with the printing surface downward, then firmly 60 holding the opposite sides parallel to the axis of the curve and against expansion, then pressing between curved dies and then removing the holding means and allowing the support and bed to assume its original 65 flat condition by reason of their resiliency.

Dated New York, January 5, 1909.

PATRICK M. FURLONG.
